PICK SHAFT SNUBBER

Francis Gerard Lake, New York, N. Y., and Elvin A. Mastriani, Newark, N. J., assignors to The M. W. Kellogg Company, Jersey City, N. J., a corporation of Delaware

Application July 16, 1947, Serial No. 761,380

3 Claims. (Cl. 139—147)

1

The present invention relates to a pick shaft snubber for fly shuttle looms.

The conventional loom picking mechanism comprises a pick cam shaft, a pick cam thereon, and a pick cam follower riding on said pick cam and mounted on a pick arm of a bell crank affixed to a pick shaft. The other pick arm of the bell crank has a connection with one end of a lug stick. The other end of the lug stick is connected to a lug strap adapted to engage the picker stick and throw it at the proper time for picking.

The toe section of the pick cam which serves to draw the picker stick inwardly towards the loom, rises abruptly, and as a result, imparts to the cam follower sufficient momentum to overthrow said follower substantially radially outwardly beyond the peak of said cam toe section and out of contact with the active surface of said cam.

One object of the present invention is to provide a new and improved pick shaft snubber which checks the overthrow of said pick shaft with a minimum of shock and strain on the loom parts.

Another object is to provide a new and improved pick shaft snubber which, while it permits the normal overthrow movement of the pick shaft, applies the checking load at such a distance from the center of the pick shaft that the checking load necessary is comparatively small and the distance through which the checking load is effective is much greater than usual so that the checking action is smooth and with minimum of shock effect on the loom parts.

As a feature of the present invention, the pick shaft snubber comprises a substantially upright snubber leaf spring secured at its lower end near the base of the loom, and adapted to be pressed at its upper free end during overthrow movement of the pick shaft by one of the pick arms of the bell crank secured to said pick shaft. The checking impact of the bell crank arm during its overthrow movement is thereby transmitted through the snubber directly to the base portion of the loom where said loom is most rigid and stable, thereby reducing shock vibrations resulting from checking action to a minimum.

Various other objects, features and advantages of the invention will be apparent from the following particular description, and from an in-

2

spection of the accompanying drawing, in which:

Fig. 1 is a front elevation of a portion of the picking mechanism on the right side of the loom, showing a pick shaft snubber embodying the present invention; and

Fig. 2 is a section of the picking mechanism taken on line 2—2 of Fig. 1.

The drawings show only the right side of the loom, but it must be understood that the picking motion and pick shaft snubber on the left side of the loom are of similar construction. The loom is shown provided with two loom sides 10, each comprising two spaced parallel vertical frame webs 11 and 12 interconnected and braced as indicated in copending application Serial No. 691,237, filed August 17, 1946. The two frame webs 11 and 12 of each loomside may carry the bearings 13 and 14 for a rocker shaft 15, to which the lower end of a lay supporting sword 16 is secured.

Only part of the picking mechanism is shown, since this in itself forms no part of the present invention, and may be of the conventional type. The parts of the picking mechanism not shown comprise in general a picker stick, at the foot of which is the parallel motion for moving the picker at the upper end of the stick parallel to the race plate. The picker stick is propelled in its picking movement by an arrangement comprising a pick cam secured to a cam shaft which may constitute the main cam shaft, as in the case of a conventional loom, or may be a separate pick cam shaft.

Engaging the pick cam is a pick cam follower supported on a pick arm 20 of the bell crank 21. The other pick arm 23 has a connection at its outer end with one end of a lug stick or rod 24. The other end of the lug stick 24 is connected to a lug strap (not shown) adapted to engage the picker stick (not shown) and throw it at the proper time for picking. Pick arms 20 and 23 are affixed to a hub 26 which is keyed to the pick shaft 22.

The pick arm 23 is shown comprising a long split sleeve 25 and provided with a pair of clamping flanges 27 on opposite sides of its split. In the sleeve 25 is an extension rod 28, which is adjustable therein to permit adjustments in the effective length of the pick arm 23, and which can

be locked in adjusted position therein by means of the bolts 30 passing through the clamping flanges 27.

In the operation of the picking mechanism so far described, as the pick cam rotates, the cam follower engages the upper section of said cam. The pick cam periphery has a toe or projecting part which rises suddenly, and which serves to impart to the cam follower the necessary impetus to rotate the pick shaft 22 clockwise (Fig. 1), and to throw thereby the picker stick inwardly towards the loom. The momentum imparted to the cam follower during this camming action is so great, as to cause said cam follower to be lifted radially outwardly beyond the peak of the cam toe.

In order to check the pick shaft in its overthrow movement, there is provided a snubber comprising an upstanding leaf spring 35 secured at its lower end to a region of the loom frame near the base, and free at its upper end to be engaged and thereby be flexed during the overthrow movement of the pick arm 23. For anchoring the lower base end 36 of the leaf spring 35, there is provided a bracket 37 secured on the outer side of the inner frame web 12 near the base of the loom by studs 38, and having a groove or channel 40 for receiving said base spring end. The leaf spring 35 is removably but firmly retained in the groove 40 by means of a dog 41, and screw members 42 passing through said dog and through said leaf spring. A resilient pad, not shown, of rubber or similar material may be interposed between the base spring end 36 and dog 41 and/or between the base spring end 36 and the bracket 37 to provide a mounting of desired resiliency for the base spring end 36.

The leaf spring 35 desirably tapers upwardly from its base section 36 to afford substantial rigidity near the base section where the greatest bending stresses are set up during checking action. The upper end of the leaf spring 35 carries a snubber spring wear pad 45, which is of suitable shock-absorbing material, such as rubber, and which has tapering sides to conform with the tapering sides of the leaf spring. The pad 45 is secured to the leaf spring 35 by fastening members 46, which may take the form of bolts or rivets passing through respective holes in said pad and with their heads confined in countersunk holes.

The snubber spring 35 is shown in Fig. 1 in relaxed position and at the instant when the bell crank 21 has reached its maximum picking speed, and is beginning its overthrow movement. In this unstressed position of the snubber spring 35, said spring will be arched and will extend generally in an oblique direction upwardly and towards the outer side of the loom towards the pick arm 23.

In the unstressed position of the snubber spring 35, shown in full lines in Fig. 1, the outer face of the wear pad 45 for a substantial part of its end length will be parallel to the longitudinal side of the pick arm 23, and will be in position shown to be engaged by said arm as the cam follower reaches the peak of the cam toe and the picker stick reaches its shuttle delivery position. In this maximum speed position of the pick mechanism, the pick shaft 22 is rotating clockwise (Fig. 1), and the momentum of the parts is carrying the pick arm 23 past this position. As the pick arm 23 continues its clockwise overthrow movement, it stresses the leaf snubber spring 35 back so that this spring reacts to take up the shock

of the parts of the pick mechanism and checks the movement of the pick shaft 22.

The picker stick is also desirably checked during its overthrow movement by a picker stick snubber (not shown). The picker stick snubber begins its checking action a short time after the picker stick has reached its maximum speed or shuttle delivery position. However, the pick shaft snubber 35 begins to act before then at the instant the pick shaft 22 reaches maximum speed. This serves to delay the lug strap with relation to the picker stick during the initial overthrow period, so that the stick moves relative to the lug strap to take up the clearance in the strap opening through which the stick passes. From then on, the lug strap and the picker stick move together to complete their overthrow stroke.

The dot and dash lines in Fig. 1 represent the extreme position of the snubber spring 35 at the end of its checking action. In this extreme position of the snubber spring 35, a substantial part of the outer length of the wear pad 45 will still remain in contact with the pick arm 23, so that the wear on said pad will be substantially uniform. Also, the relative slide movement between the pad 45 and the pick arm 23 will be at a minimum during overthrow checking action, so that said pad will be subjected to a minimum of abrasive wear action.

By anchoring the snubber spring 35 near the base of the loom, shocks due to the checking action of the spring will be transmitted to the most rigid and stable section of the loom. Therefore, no excessive shocks or vibrations incidental to this checking action are set up in the loom.

By employing a snubber spring 35 having a comparatively long leverage arm and by imposing the checking load adjacent the end of pick arms 23, the pick shaft 22 is permitted to rotate through its normal overthrow movement before it is completely arrested so that the checking action is gradual and smooth and excessive shocks and vibrations are not set up in the shaft 22 and the elements associated therewith. Also, by this arrangement the checking load applied is much less than in the prior arrangements wherein the checking load is applied near the shaft end of the cam follower pick arm.

While the invention has been described with particular reference to a specific embodiment, it is to be understood that it is not to be limited thereto, but is to be construed broadly and restricted solely by the scope of the appended claims.

55. What is claimed is:

1. In a loom of the fly shuttle type, a loomside comprising a vertical frame web, a pick shaft, a snubber leaf spring for said pick shaft, and means for mounting said leaf spring and comprising a bracket fastened to said frame web, and having a groove for one end of said leaf spring, and a clamping member for removably securing said spring end in said groove, said spring being located in position to be stressed during overthrow movement of said shaft by a member carried by said shaft to check said movement.

2. In a loom of the fly shuttle type, a pick shaft, a pick arm secured to said pick shaft, and a snubber for said pick shaft comprising a leaf spring arched in unstressed condition and mounted at its lower end with its concave side facing the outer side of the loom, said spring extending generally obliquely upwardly and outwardly with respect to the loom and towards said pick arm, and being located in position to be stressed by

said pick arm during overthrow movement of said pick arm to check said movement.

3. In a loom of the fly shuttle type, a loomside comprising a vertical frame web, a pick shaft, a pick arm secured to said shaft and having a connection to a picker stick, and a snubber for said shaft comprising an upstanding leaf spring, means for removably mounting the lower end of said spring to said frame web near the base of the loom, and a wear pad of shock-absorbing material secured to the upper end of said spring, said spring being located in position to cause said wear pad to be engaged by said pick arm during overthrow movement of said pick arm to check said movement.
